Watson E. Cobman ATTORNEYS.

UNITED STATES PATENT OFFICE.

GEORGE BAKER, OF PERSHING, OKLAHOMA.

COMBINED GAS AND OIL NOZZLE.

Application filed June 9, 1925. Serial No. 36,030.

To all whom it may concern:

Be it known that I, GEORGE BAKER, a citizen of the United States, residing at Pershing, in the county of Osage and State of Oklahoma, have invented certain new and useful Improvements in Combined Gas and Oil Nozzles, of which the following is a specification, reference being had to the accompanying drawings.

10 This invention relates to gas or combined gas and oil nozzles and more particularly to a device of this character intended for use in combination with a combustion chamber and an air inlet control device constructed 15 in accordance with my copending application for patent on gas burners, Serial No. 36,029, filed June 9, 1925.

In the application above identified, I have disclosed a combustion chamber and a fuel 20 drum in axial alignment with the inlet of the combustion chamber and a sleeve slideable upon the drum and inlet and by its position controlling the amount of air admitted for mixture with the fuel as ejected 25 from the drum.

An important object of this invention is to provide a fuel drum of such character that steam may be employed for supplying 30 pressure to the gas and for injecting the gas into the combustion chamber where the natural pressure of the gas or fuel is not sufficient to enable it to be so used.

A still further object of the invention is to provide a device of this character so constructed that in addition to its function as 35 a means for stepping up the pressure of gas, it may be employed for atomizing and evaporating fuel oil for use in the burner so that the burner may continue in use when no gas 40 is available or the action of the gas may be augmented as is found desirable.

Other objects and advantages will become 45 obvious in the course of the following description.

My invention is illustrated in the accompanying drawings wherein:—

Figure 1 is a longitudinal sectional view taken through a burner having a combined gas and oil nozzle constructed in accordance 50 with my invention;

Figure 2 is an enlarged longitudinal sectional view taken through the nozzle structure;

Figure 3 is an end elevation thereof; 55 Figure 4 is a section on the line 4—4 of Figure 2;

Figure 5 is a section on the line 5—5 of Figure 2;

Figure 6 is a section on the line 6—6 of Figure 2;

Figure 7 is an end elevation of a modified nozzle construction;

Figure 8 is a section on the line 8—8 of Figure 7; and

Figure 9 is an end elevation of the steam chamber employed in the form of nozzle shown in Figures 7 and 8.

Referring now more particularly to the drawings, the general structure with which the drum is to be employed includes a combustion chamber 10 which is fixed and has an inlet 11 and an outlet 12. The outlet may be provided with a flame spreader 13, the construction and mounting of which will hereinafter be more fully set forth.

Arranged in alignment with the inlet 11 is a drum 14, the construction of which will be hereinafter more fully described. This drum is held in fixed position by a gas line 15, a steam line 16 and in some instances, as will be hereinafter more fully set forth, by an oil line 17. Slidably engaged with the outer surface of the gas drum and the inner surface of the tubular inlet 11 of the combustion chamber is a sleeve 18 which, together with its associated parts, constitutes the air inlet control means. The construction of this air inlet control means is fully set forth and claimed in the co-pending application above referred to and is merely illustrated in the present instance for the purpose of showing the manner of use of the drum. The drum 14 has an inlet 19 with which the gas line 15 communicates and which is formed at one end of the drum.

The opposite end of the drum has a wall 20 which has a central aperture 21 and grouped about this aperture are a plurality of nozzles 22 which project outwardly from this end wall. Arranged within the drum adjacent the end wall 20 is a steam chamber 23 preferably circular in form and having projecting toward this rear wall and in alignment with the bores of the nozzles 22 jet nozzles 24. This chamber has likewise projecting therefrom an axial nozzle 25 which is directed through the axial opening 21 of the end wall and which is of such length that it projects beyond the outer ends of the nozzles 22. Arranged adjacent the inlet end of the drum is an inlet fitting 26 having a T-head, both ends of which are

open and with one end of which the steam line 16 is engaged. The opposite end of the fitting will accommodate either a steam line leading to a further drum or a plug sealing this end. Interiorly of the drum, this inlet communicates with a conduit 27 extending longitudinally of the drum and communicating with the chamber 23 adjacent the lower end thereof and at the rear wall thereof. Extending rearwardly from the rear wall of the steam chamber is a semi-circular flange 28 receiving within its bight the conduit 27, the end of this flange being closed by a wall 29.

15 Arranged adjacent the inlet end of the drum at the upper surface thereof is an oil inlet 30 which is similar to the steam inlet 26 and which interiorly of the drum communicates with a forwardly and downwardly inclining conduit 31, the lower end of which is positioned to discharge into the trough formed by the rear wall of the chamber the semi-circular flange 28 and the wall 29. Mounted in the walls of the chamber 25 are tubes 32, one of which is arranged at each side of the lowermost nozzle 22 which is vertically below the axis of the drum. Each of these tubes projects from the front face of the chamber 23 a short distance and 30 has its ends open so that one end is in communication with the trough and the opposite end in communication with the interior of the drum 14 adjacent the wall 20 thereof.

35 In the use of this form of my device, when gas alone is being used, steam entering through the inlet and passing through the chamber is injected at the nozzles 24 and passing through the nozzle 22, because of the form of these nozzles, sets up a suction within the drum, withdrawing gas from the drum and reducing the pressure of the drum so that low pressure gas will readily enter thereinto. At the same time, the steam and gas are thoroughly mixed and in passing 40 from the nozzles will be further mixed with air entering through openings formed in the sleeve, the amount of air which is mixed depending upon the adjusted position of the sleeve. The central steam nozzle will serve to produce a blast and a tendency toward a vacuum at the nozzles 22 so that the mixture ejected from these nozzles will be drawn into the steam passing from the nozzle 25 and thoroughly mingle therewith. 45 The gas being heated will, of course, ignite very readily and will provide a steady hot flame at the outlet 12 of the combustion chamber. When oil is being used, the oil passing from the pipe 31 into the trough 50 is highly heated with the result that a certain proportion thereof is vaporized and passes off with the gas through the nozzles 22. The remainder of this oil through the suction created at the nozzle end of the drum 55 will be drawn off in the form of a spray and

intermingle with the gaseous fuel and steam. In the combustion chamber, the additional heat supplied together with the steam will serve to completely evaporate this oil so that gas is supplied at the outlet 12 for burning. It will be obvious that where no oil is to be employed in the burner, the form of construction shown in Figures 7 to 9 may be employed, the trough formed by the flange 28 and end wall 29 and the oil inlet and conduit 31 being eliminated as are the tubes 32.

With a device of this character, I preferably provide at the outlet of the burner a spreader such as more clearly shown in Figure 1. This spreader is formed by providing the outlet 12 which is tubular with an outstanding flange 33, the outer edge of which is raised above the inner edge so that a dish effect is obtained. Supported in alignment with the outlet is a concaved disk 34 having an axial opening 35 and above this disk is arranged a solid concaved disk 36, the concaved seats of the disk being arranged upwardly. In supporting the disks, I preferably provide a rod 37 axially directed through the outlet 12 and threaded at its lower end in the wall of the combustion chamber.

To the outer end of this rod, the disk 36 is threaded and the outer edge of this disk has depending arms 38, the lower ends of which are secured to the disk 34. With a spreader of this character, a portion of the contents of the combustion chamber will 50 pass outwardly between the disk 34 and the flange 33 while the other portion thereof will pass through the opening 35 and impinge against the lower face of the disk 36 and pass out between the disks 35 and 36, thus providing a double circular flame which the pressure of the blast emitted when steam is being employed to provide means for drawing gases into the gas drum.

Since the construction hereinbefore set forth is capable of a certain range of change and modification without materially departing from the spirit of my invention, I do not limit myself to such specific structure except as hereinafter claimed.

I claim:—

1. A gas burner drum having an inlet and provided in one wall thereof with a plurality of venturiform outlets arranged upon a circle, a steam chamber within the drum and opposing said wall, said chamber having an inlet and having outlet nozzles corresponding in number and arrangement to the outlets of said wall and directed axially thereof, a steam conduit communicating with the inlet of the chamber and extending longitudinally of the interior of the drum, an oil pan within the drum through which said steam conduit extends and means for delivering oil to the pan.

2. A gas burner drum having an inlet and provided in one wall thereof with a plurality of venturiform outlets arranged upon a circle, a steam chamber within the drum and opposing said wall, said chamber having an inlet and having outlet nozzles corresponding in number and arrangement to the outlets of said wall and directed axially thereof, a steam conduit communicating with the inlet of the chamber and extending longitudinally of the interior of the drum, an oil pan within the drum through which said steam conduit extends, means for delivering oil to the pan, the drum forming one end wall of the pan and tubes communicating with said pan and extending through the steam chamber and having their outer ends arranged upon opposite sides of one of the nozzles of the chamber.
3. A gas burner drum having an inlet and provided in one wall thereof with a plurality of venturiform outlets arranged upon a circle, a steam chamber within the drum and opposing said wall, said chamber having an inlet and having outlet nozzles corresponding in number and arrangement to the outlets of said wall and directed axially thereof, said steam chamber having a further axially disposed outlet nozzle projecting through said wall of the burner drum and having its outer end extended beyond the outer ends of the outlets of the drum.
4. A gas burner drum having an inlet and provided in one wall thereof with a plurality of venturiform outlets arranged upon a circle, a steam chamber within the drum and opposing said wall, said chamber having an inlet and having outlet nozzles corresponding in number and arrangement to the outlets of said wall and directed axially thereof, said steam chamber having a further axially disposed outlet nozzle projecting through said wall of the burner drum and having its outer end extended beyond the outer ends of the outlets of the drum, the steam conduit communicating with the inlet of the chamber and extending longitudinally of the interior of the drum and an oil pan within the drum through which said steam conduit extends.
5. A gas burner drum having an inlet and provided in one wall thereof with a plurality of venturiform outlets arranged upon a circle, a steam chamber within the drum and opposing said wall, said chamber having an inlet and having outlet nozzles corre-
- sponding in number and arrangement to the outlets of said wall and directed axially thereof, said steam chamber having a further axially disposed outlet nozzle projecting through said wall of the burner drum and having its outer end extended beyond the outer ends of the outlets of the drum, the steam conduit communicating with the inlet of the chamber and extending longitudinally of the interior of the drum, an oil pan within the drum through which said steam conduit extends, said steam chamber forming one end wall of said oil pan.
6. A gas burner drum having an inlet and provided in one wall thereof with a plurality of venturiform outlets arranged upon a circle, a steam chamber within the drum and opposing said wall, said chamber having an inlet and having outlet nozzles corresponding in number and arrangement to the outlets of said wall and directed axially thereof, a steam conduit communicating with the inlet of the chamber and extending longitudinally of the interior of the drum, an oil pan within the drum through which said steam conduit extends and means for delivering oil to the pan and outlets for the oil pan extending through the steam chamber and having their outer ends arranged between adjacent nozzles of the steam chamber.
7. A gas burner drum having an inlet and provided in one wall thereof with a plurality of venturiform outlets arranged upon a circle, a steam chamber within the drum and opposing said wall, said chamber having an inlet and having outlet nozzles corresponding in number and arrangement to the outlet of said wall and directed axially thereof, said steam chamber having a further axially disposed outlet nozzle projecting through said wall of the burner drum and having its outer end extended beyond the outer ends of the outlets of the drum, the steam conduit communicating with the inlet of the chamber and extending longitudinally of the interior of the drum, an oil pan within the drum through which said steam conduit extends and outlets for the oil pan extending through the steam chamber and having their outer ends arranged between adjacent nozzles of the steam chamber.

In testimony whereof I hereunto affix my
signature.

GEORGE BAKER.
